[57] ABSTRACT

A side sill arrangement in which a first channel member which forms a part of a side frame is joined to a second channel member which forms a part of the underframe assembly. The joined channel members form a hollow side sill beam assembly which extends longitudinally of the railway car to function as a strengthening member having sufficient strength to eliminate the need of a through car center sill. The formed beam includes hollow portions used to conceal fasteners which attach internal members thereby rendering the side sill with a smooth unobstructed outside surface permitting it to be used as an external member without additional covering.

SIDE SILL FOR RAILWAY VEHICLE

SUMMARY OF THE INVENTION

This invention relates to an improved side sill arrangement for use in railway passenger vehicles and it is a principal object of the present invention to provide an improved strength two-part side sill which will support crossmembers and provide sufficient structural strength to a railway passenger car to thereby eliminate the need for a center sill. The present side sill consists of an integral combination of two side members, one initially assembled with the side frame assembly and a second channel member initially assembled with and part of the underframe assembly.

It is also an object of the invention to provide a novel side sill arrangement in the form of a hollow beam extending longitudinally of the car and having sufficient strength to resist horizontal and vertical loading normally encountered in car operation and testing.

It is another object of this invention to provide an extruded side sill member having depending horizontal portions which may be utilized in attaching and supporting transverse members.

It is yet another object of the present invention to provide a side sill arrangement which includes hollow web portions which are utilized to conceal fastening devices.

BRIEF DESCRIPTION OF THE DRAWINGS

FIG. 1 is a top plan view of a railway car underframe with a central portion removed; and

FIG. 2 is an enlarged section view taken along line 2—2 of FIG. 1 with the car side frame assembled to the underframe.

DETAILED DESCRIPTION

Referring now to the drawings and in particular to FIG. 1, there is illustrated a railway passenger car body supporting structure 10 which includes end sills 11, stub draft sills 12 and laterally extending bolsters 13. A coupler (not shown) is mounted in each of the draft sills 12 and extends therefrom. The bolsters 13 extend transversely of the car and are connected to the side sills 14 and the stub sill 12 to transmit coupler forces through the side sills 14. No center sill is used. Cross supports 14a, having a Z-shape, extend outward at the stub sill 12 to the side sill 14 and are used to attach the subfloor sheets 14b, 14c and to connect the longitudinally extending support bars 15. An end plate 15a is attached as by weldment to the outside ends of the cross supports 14a and used for attaching the cross support 14a to the side sill 14 as by fastener 15b. The car body includes a sidewall or side frame assembly 16, a roof structure (not shown) and an underframe of floor unit 17. There is a side frame assembly 16 on each side of the car and extending longitudinally thereof. The underframe unit 17 and the roof (not shown) extend from one sidewall to the other. In assembly the sidewall units are moved laterally inward and connected with the floor underframing 17, then the roof unit is connected to the top portions of the sidewall units.

Referring now to FIG. 2, the wall assembly 16 includes: exterior side sheets 18; longitudinally spaced Z-shaped side posts 19 having flange portions 19a, 19b; interior sheeting members 20 and the first channel member 21. The side sheet 18 and the inside sheeting 20 are welded to the flanges 19a, 19b of the side posts 19 as by weldments at 21a, 21b. The first channel member 21 includes a continuous stepped or cutout portion 22 to receive the side sheet 18 and thereby produce a smooth connection between two members 18, 21. A second sheet member 21c is spaced inboard of the sheet 20 to provide a duct 21d for a heating element. The sheet member 21c is supported by the angle bracket 21e. A top flange 23 is used to secure the channel member to the side posts 19 and includes a vertically depending lip portion 24 which is used in alignment and attachment of the first channel member 21 to the underframe assembly 17. Channel member 21 includes an arcuate portion 25 extending downward from the cutout 22 and

terminating in a connection with the outside lower depending vertical web portion 26. A lower horizontal depending flange portion 27 extends from the vertical web portion 26 and is utilized for alignment and attaching purposes.

The floor unit or underframe assembly 17 includes: laterally extending Z-shaped crossbearers 28, 29, separated by a car width metal subfloor sheet 19a; a car width flooring assembly 30 including a tile or rubber top 30a; metal sheets 30b, 30c; wood panel 30d; and a second longitudinally extending channel member 31. Between the subfloor sheet 29a and the metal sheet 30c is an enclosed airspace which may be filled with insulation to improve soundproofing and thermally insulate the car. The channel member 31 includes an upper flange 32, an intermediate flange 33, and a lower or bottom flange 34. Connecting the upper flange 32 and intermediate flange 33 is a vertical web portion 35. The intermediate flange 33 is connected to the bottom flange 34 by diagonal portions 35a, 35b, 35c; and by vertical web portions 36, 36a, 36b. Longitudinally spaced drainage means 37 are included in the second channel member 31.

The car underframe assembly 17 is assembled as a unit and is fastened to the sidewall assembly 16 which is also assembled as a separate unit. Assembly of the two units 16, 17 is simplified and facilitated by the side sill channel members 21 and 31 which are positioned in abutting relation as illustrated in FIG. 2 and then securely fastened as by weldments W and fasteners 40. Exterior welds and seams are burnished smooth to leave no evidence of fabrication. Four points of contact 41, 42, 43, 44 are provided for assembly purposes thereby simplifying the assembly and welding of the two units 16, 17. When the two channel members 21 and 31 are securely fastened they form the car side sill which is a hollow beamlike supporting structure extending longitudinally of the car which will function to resist horizontal, vertical and other loads applied to the car and also eliminate the need for a center sill. The hollow portions 45, 46 formed upon assembly of the two channel members provide a space for concealing fasteners 15b, 48 which are used to attach transversely extending underframe members such as bolsters 13, end sills 11 or other members. The integrally formed flanges and offset portions of the extruded channels 21, 31 provide surfaces for mounting and attaching various members. The ease of manufacturing extruded aluminum channel members and the various cross sections which are afforded has eliminated the need for welding together individual flat sheet or rolled pieces and thereby a more economical lightweight side sill has resulted.

The foregoing description and drawings merely explain and illustrate the invention and the invention is not limited thereto, except insofar as the appended claims are so limited, as those skilled in the art who have the disclosure before them will be able to make modifications and variations therein without departing from the scope of the invention.

What is claimed is:

- 55 1. In a center-sill-less railway vehicle having a sidewall assembly and a floor assembly including crossbearers and floor members, said sidewall assembly including side sheets, sidewall posts and a longitudinally extending first channel member, a second longitudinally extending channel member along the outside margin of said floor assembly, said first and said second channel members being provided with horizontal and vertical mating portions, said mating portions being used both in aligning the sidewall assembly with the floor assembly and connecting the sidewall assembly to the floor assembly, said connected channel members forming a hollow beam structural member of side sill having:
  - first and second hollow portions defining beam portions which impart strength to the combined channel members, and having laterally, inwardly extending flange portions providing mounting and attaching surfaces for said crossbearers and said floor members.
- 60 2. The invention according to claim 1, and said first and said second channel members each comprising a one-piece extruded construction.
- 65 3. The invention according to claim 1, and
- 70 4. The invention according to claim 1, and
- 75 5. The invention according to claim 1, and

said second channel member including top, intermediate and lower flange portions and having spaced drain means extending vertically through openings in said top and said intermediate flange portions.

4. The invention according to claim 1, and
 said first channel member having an upper, outer, curved portion having a cutout end portion and said side sheets having a bottom portion received in said cutout portion resulting in a smooth joint between the sheet and the first channel member.
5. The invention according to claim 1, and
 said second channel member including transversely inwardly extending flange portions being used in fastening and supporting said crossbearers and said floor members.
6. The invention according to claim 5, and
 said inwardly extending flange portions being continuous along the length of said second channel member.
7. In a railway passenger vehicle having spaced end sills connected through a stub center sill to an inwardly spaced body bolster, and having a sidewall assembly and a floor assembly, a side sill including:
 extruded means extending longitudinally of said vehicle between said end sills and attached to said end sills and to said bolsters,
 upper and lower flange portions being connected by vertically extending web portions to thereby define a beam means providing vertical strength to said extruded means,

5

laterally extending flange portions depending from said vertical portions and said flange portions imparting transverse beam strength to said extruded means.

8. The invention according to claim 7, and
 said laterally extending flange portions extending inward of said vehicle and being used for supporting and attachment of said floor assembly.

9. The invention according to claim 7, and
 said laterally extending flange portions having spaced drain means extending vertically therethrough.

10. The invention according to claim 7, and
 said side sill including a first channel member attached to said sidewall assembly and a second channel member attached to said floor assembly,
 said first and said second channel members being secured together to form said beam means.

11. The invention according to claim 7, and
 said side sill including hollow portions formed between said vertically extending web portions and said laterally extending flange portions thereby forming a hollow beam structural member possessing integral strength to resist horizontal and vertical loading.

12. The invention according to claim 11, and
 said hollow portions being utilized to conceal fasteners used in attaching said floor assembly.
